US00D785274S

(12) **United States Design Patent** (10) **Patent No.:** **US D785,274 S**
Mikolajczyk et al. (45) **Date of Patent:** **** Apr. 25, 2017**

(54) **CLUSTER BOX MAIL DELIVERY UNIT**29/14; A47G 29/141; A47G 29/142;
A47G 29/148; A47G 29/16(71) **Applicant:** **United States Postal Service,**
Washington, DC (US)

See application file for complete search history.

(72) **Inventors:** **Ryszard K. Mikolajczyk**, Chicago, IL
(US); **Taurris D. Baskerville**,
Schaumburg, IL (US)(56) **References Cited**

CLAIM

The ornamental design for a cluster box mail delivery unit, as shown and described.

DESCRIPTION

FIG. 1 is a perspective view of a cluster box mail delivery unit showing our new design;
FIG. 2 is a front view thereof;
FIG. 3 is a right side view thereof;
FIG. 4 is a left side view thereof; and,
FIG. 5 is a top view thereof.
The rear and bottom views form no part of the claimed design.
The broken lines form no part of the claimed design.
